UNITED STATES PATENT OFFICE.

HARRY S. HART, OF CHICAGO, ILLINOIS, ASSIGNEE TO RODGER BALLAST CAR COMPANY, OF CHICAGO, ILLINOIS, A CORPORATION OF MAINE.

BALLAST CAR.

Application filed July 17, 1924. Serial No. 726,429.

The present invention relates to ballast cars.

More particularly the present invention relates to railway dump cars designed for the purpose of expeditiously depositing ballast between the tracks and outside of the tracks upon which said cars are mounted. It is desirable to deposit ballast from a ballast car as said car travels along the tracks, and if special means are not provided for preventing flooding of the rails, such flooding is liable to occur, causing serious delays and possible derailment.

The present invention constitutes an improvement over the structure described and claimed in the patent to Summers No. 861,552 and has for one of its objects the provision of means whereby ballast may be deposited without serious danger of flooding the rails.

A further object is to provide a car having dump means so arranged that dumping may be accomplished either between the rails or outside of the rails, the parts being so designed that a maximum amount of ballast may be safely deposited without danger of derailment.

A further object is to provide a ballast car of the type disclosed in the Summers patent referred to, from which ballast may be deposited expeditiously and with the exercise of a minimum of discretion on the part of the operator of the dumping mechanism of the car.

Further objects will appear as the description proceeds.

Referring to the drawing—

Figure 1 is a more or less diagrammatic sectional view taken transversely of a dump car, showing in full lines the dump doors in closed position and in broken lines the positions for dumping between the rails; and

Figure 2 is a view of the construction shown in Figure 1 but with the doors in position to deposit ballast laterally of the rails.

The numeral 1 indicates a railway ballast car having the side walls 2—2, which may be suitably braced by means of stakes 3—3. Mounted contiguously to the side walls 2—2 are the bottom walls 4—4 sloping downwardly and inwardly from the side walls 2—2. The numerals 5—5 indicate the center sills of the car, which center sills are provided with the cope 6, which cope provides a shedding member whereby lading is shed

either to the right or to the left of the sills 5—5.

The numerals 7—7 indicate swinging doors, which swinging doors are mounted in such a manner that lading may be deposited selectively from either of the side edges thereof. The doors 7—7 may be identical and when in closed position may engage with the under sides of the sills 5—5 and the sloping floors 4—4 to form hopper bottoms. Insurance of the proper seating of said doors may be accomplished by any preferred means, as for example the means described in the Summers Patent No. 861,552 above referred to. Chains 8—8 are provided, which chains are controlled by the rotatable shaft 9. Rotation of shaft 9 in one direction will result in the lowering of those edges of the doors 7—7 which are located adjacent to the center sills 5—5. Rotation of the shaft 9 in the opposite direction will tend to raise said edges of the doors 7—7. The outer edges of the doors 7—7 are controlled by the chains 10—10, each of which chains is controlled by a corresponding rotatable shaft 11. The shafts 11—11 may be independently rotatable and rotation of either of said shafts in one direction will result in the lowering of the adjacent edge of the doors 7 away from the corresponding sloping floor 4. Rotation of said shaft 11 in the opposite direction will result in the raising of the adjacent edge of the door 7 to closing position relative to the sloping floor 4. Brackets 12—12 are provided at the side edges of each of the doors 7—7, said brackets having suitable eye portions for receiving the chain 10.

The wheels of the car are indicated by the numerals 13—13, which wheels ride upon the rails 14—14. Disposed longitudinally of the car in regions intermediate of the planes of the wheels on the two sides of the car are the throttling beams 15—15, which beams may be supported in any preferred way at their longitudinal extremities and which may be provided with the struts 16—16 for support midway of the length of said beams. Said struts 16—16 may be carried by the center sills 5—5. The beams 15—15 are shown in the form of channels having their flanges extending downwardly and outwardly, whereby the back sides of said channels constitute shedding members for ballast. The back sides of said beams

15—15 also constitute stop members for the dump doors 7—7 in the swinging movement of said dump doors 7—7 for center dumping.

The lower edges of the throttling beams

- 5 15—15 provide means for limiting the pile of ballast deposited between the rails 14—14. The numerals 17—17 indicate lines representing the angle of repose of rock ballast. The lower edges of the guard members
- 10 15—15 coincide with the lines 17, which lines 17 extend through the planes of the rails 14—14 at regions adjacent to said rails but below the tops thereof.

As noted above, the doors 7—7 are independently controllable for side dumping, so that side dumping may be accomplished either on one side of the rails 14—14, on the other side of said rails, or simultaneously on the outer sides of said rails 14—14. At 20 the time that the doors 7—7 are swung to position or positions for side dumping, the edges of said doors centrally of the car should preferably be drawn up into proximity to the center sills 5—5. At a certain 25 position of each of the doors 7—7 the ballast will tend to flow freely therefrom. Such position is indicated by the doors in Figure 2. The doors 7—7 are so designed that when said doors are in the position referred to, that is—the position which permits the free flow of ballast, the outer edges of said doors will limit the pile of lading to a region such that flooding of the rails will be avoided. The numerals 18—18 in 30 Figure 2 indicate the angle of repose of rock ballast and said lines 18—18 are so located that they extend through the vertical planes, including the rails 14—14, at regions adjacent to said rails but below the tops thereof. 35 The outer swinging edges of the dump doors 7—7 lie approximately in the planes indicated by the numerals 18—18. Said outer swinging edges, therefore, define the limits of the piles of ballast deposited outside of the rails 14—14. Railway ballast cars are commonly operated at a speed such that the operator may walk along with said cars as the depositing of ballast is being accomplished. This speed of the car may be 40 45 taken to be approximately four miles per hour.

It will be noted that the throttling beams are so placed that their lower edges are in a plane substantially coincident with the angle of repose of the ballast material, which plane intersects the rail below the top thereof, so that a maximum amount of ballast may be deposited between the rails without flooding them. It will be further noted that the inner swinging edges of the doors are so related to these throttling beams that the inner swinging edges are at all times within a vertical plane extending upward from the upper edge of the throttling beams. 50 55 60 65 70 75 80 85 90 95 100 105 110 115 120 125 130 135 140 145 150 155 160 165 170 175 180 185 190 195 200 205 210 215 220 225 230 235 240 245 250 said door in its opening movement for center dumping, said throttling means having a lower edge extending longitudinally of said car, which edge lies in a plane representing the angle of repose of the ballast material, which plane intersects the plane of the adjacent rail at said rail and below the top thereof.

5. A car for carrying and depositing ballast having doors each hinged to drop either from a point adjacent to the center sill or from a point adjacent to the side of said car, each of said doors being of such length that when dropped from the side the outer edge of either of said doors will lie in a plane substantially representing the angle of repose of said ballast, which plane intersects the vertical plane of the adjacent rail adjacent to or below the top of said rail, and
- 10 a pair of throttling beams beneath the level of the center sill, said beams being disposed in position to limit deposit of said ballast at the angle of repose of said ballast, the base of which angle is at said rail below the tops thereof, the inner swinging edges

of said doors being always within the vertical planes extending upwardly from the upper edges of said throttling beams.

6. A ballast car, including means for dividing said car into two laterally placed hopper bottoms, each of said hopper bottoms being provided with a door swingingly mounted as a unit adjacent to the two sides thereof and controlling means whereby said door may be opened as a unit for either center or side dumping, a throttling member for forming a stop for the opening movement of said door for center dumping, the lower edge of said throttling member and the outer edge of said door, when said door is swung to a position from which ballast material flows freely therefrom for side dumping, lying in planes representing the angle of repose of the ballast material which intersect the plane of the adjacent rail upon which said car is mounted at said rail below the top of said rail.

Signed at Chicago, Illinois, this 14th day of July, 1924.

HARRY S. HART.
